MINIATURE ROASTER

Kenneth C. Gulden, Milwaukee, Wis.

Application June 29, 1955, Serial No. 36,745

Term of patent 14 years

(Cl. D81—10)

FIG. 1

Fig. 2 is a top plan view of the same, and

Fig. 3 is a side elevational view of the same.

I claim:

The ornamental design for a miniature roaster, as shown.
